UNITED STATES PATENT OFFICE.

SAMUEL E. STOKES, OF PHILADELPHIA, PENNSYLVANIA.

CONTROLLING DEVICE FOR ELEVATORS.

SPECIFICATION forming part of Letters Patent No. 439,440, dated October 28, 1890.

Application filed May 1, 1889. Serial No. 309,184. (No model.)

To all whom it may concern:

Be it known that I, SAMUEL E. STOKES, a citizen of the United States, and a resident of Philadelphia, Pennsylvania, have invented 5 certain Improvements in Valve-Controlling Devices for Elevators, of which the following is a specification.

My invention relates to improvements in starting, stopping, and reversing gear for elevators, in which the attendant on the cab or car controls the main change or reversing valve or auxiliary or pilot valve by simply operating a hand-wheel or lever.

The object of my invention is to so connect 15 the hand-wheel on the cab with the controlling mechanism—*i. e.*, the valve or lever—that the two ends of the ropes, chains or bands connecting the hand-wheel with the controlling mechanism will be stationary, and the 20 slack caused by the raising or lowering of the cab will be taken up by intermediate mechanism mounted on the piston-rod, as fully described hereinafter, reference being had to the accompanying drawings, in which—

25 Figure 1 is a view illustrating my invention in its simplest form, the rope passing over a sheave on the head of the piston-rod of a vertical cylinder. Fig. 2 is a perspective view of the wheels, sheaves, and ropes, with the 30 bearings for the several parts omitted. Fig. 3 is a view showing my invention applied to a horizontal cylinder for operating an elevator-car; and Fig. 4 is a view also showing my invention applied to a horizontal hydraulic 35 elevator-cylinder, in which the lifting-rope of the car also performs the function of controlling the valves.

40 Referring to Fig. 1, A is the elevator-well; B, the cab; C, the rope, by which the elevator is raised, said rope passing over a sheave C', as usual, and connected by any suitable lifting mechanism.

D is the controlling device for the elevator, 45 which may be either in the form of a three-way valve, as shown in the figures, or in the form of a clutch or lever, depending altogether upon the style of elevator used.

E is the shaft, carrying in the present instance a toothed drum F on the outside of the 50 cab, and on the inside a suitable hand-wheel

or lever G, as shown more clearly in Fig. 2; but this construction may be modified, as circumstances require. The drum F in the present instance has a series of sprocket-teeth on its periphery, which engage with the chain 55 portion *a* of the rope I.

H H are two independent sheaves hung loosely on an axle, attached as shown in Fig. 1, to a slide H'. The two portions of the rope I pass around these sheaves. The slide has 60 a slight vertical movement sufficient to take up the expansion or stretch of the rope. Otherwise it is practically stationary. The rope also passes around two sheaves J J on an axle, which is mounted on the piston-rod M 65 of the cylinder M'. Both ends of the rope then pass to the drum K, to which they are secured, as shown in Fig. 2, one to one side and the other to the other side of the drum. Any movement of the wheel G will be transmitted to the drum G through the rope I, and as each portion of the rope passes around a loose sheave J or K the friction is considerably reduced. The rope in the present instance is double for moving the valve in both 75 directions; but it will be understood that I do not limit myself to this double rope, as a single rope may be used for moving the valve in one direction and a weight on the valve moving it in the opposite direction, although 80 I prefer the double rope, as shown in Fig. 2.

Other forms of mechanism or devices for holding the chain or rope in position on the wheels F and K may also be employed without departing from my invention. It will 85 thus be seen that the portion of the rope passing around the sprocket-wheel F is stationary as regards any motion of the car, while the portion attached to the wheel K is also stationary; but as the car is raised or lowered, the 90 end of the rope carried by the car will consequently be raised or lowered with the car, and to allow for this movement sufficient slack must be given to the rope. In all cases the car moves at the same proportionate rate as the 95 piston-rod M. Consequently by mounting the sheaves J on the head of the piston-rod the slack of the rope will be taken up and given out as the car descends or ascends, and the controlling-valve can be moved by the oper- 100

ator simply turning the hand-wheel at any point during the ascent or descent of the cab. If, for instance, a hydraulic elevator is used, the valve for controlling the motive liquid 5 would be simply a three-way piston-valve, the piston being connected to the wheel K, so that when the operator moves the hand-wheel G in one direction the valve will be moved so as to allow the motive liquid to flow above the piston, and consequently raise the cab; but if the hand-wheel is moved in the opposite direction the cab will be lowered, as the motive liquid will flow under the piston; but if the hand-wheel is moved to a central position the valve 15 will likewise be moved to a central position, closing the valve, and consequently stop the cab at any point required.

I have found in practice that it is objectionable to have sheaves on the car traveling continuously over a fixed rope, as the constant motion of the car in time wears not only the rope away, but also the bearings for the sheaves, and these sheaves are generally in such position that they are not accessible 25 without difficulty, and are necessarily made smaller than advisable; but by having the mechanism shown a simple wheel or lever is used on the cab and a simple wheel or lever on the valve-stem, and take-up mechanism between the two ends consisting of a weighted sheave or equivalent to keep the rope taut at all times.

In Fig. 5 I have shown my improvement ap-

plied to a horizontal hoisting-cylinder, in which the ropes I pass around sheaves H, over 35 stationary journaled sheaves J, and around stationary journaled sheaves J², around movable sheaves J³, back around sheaves J to the wheel K controlling the valve. In this instance the rope is compounded the same as 40 the hoisting-rope. This compounding of the rope may be carried to a greater extent, depending upon the lift of the elevator.

In Fig. 6 the lifting-rope of the car is used as the valve-controlling rope, the rope passing 45 up over sheaves C' at the top of the elevator-shaft, down around sheaves H², around sheaves H³, on a piston-rod of the cylinder, around the sheaves H² again, then around the sheaves H³, and connected to the lever K', 50 controlling the valve.

I claim as my invention—

The combination of the valve-controlling rope connected to an operating device on the car and to the valve-operating mechanism, 55 with a take-up pulley carried by the piston-rod of the operating-cylinder and applied to the rope at a point between the operating device and valve, substantially as specified.

In testimony whereof I have signed my 60 name to this specification in the presence of two subscribing witnesses.

SAMUEL E. STOKES.
